BOTTLE LABELING MACHINE

George M. Biner, Phoenix, Ariz.

Application March 17, 1937, Serial No. 131,273

15 Claims. (Cl. 216—54)

Reference is made to my co-pending application Serial No. 149,123, filed June 19, 1937.

My invention relates to bottle labeling machines and has for its objects the provision of a machine of simplified structure having a minimum number of parts, whereby its operation, cost of manufacture, and cost of maintenance is minimized; a second object is to provide a machine for the mechanical labeling of bottles wherein the motions of the various parts are confined to simple swinging movements, whereby guides and guide channels are eliminated; and a third object is to provide a mechanism of the type described wherein operation of the several parts is produced by means of simple cranks in a manner to eliminate the necessity for cams and cam followers and adjunctive guides, thereby reducing the cost of manufacture and simplifying adjustment of the various parts. Other objects will appear hereinafter.

I attain the foregoing objects by means of the construction, devices and combination of parts shown in the accompanying drawings, in which—

Fig. 1 is a side elevation of my machine; Fig. 2, a right hand end elevation thereof; Fig. 3, a fragmentary plan section thereof, taken substantially on line 3—3, Fig. 2; Fig. 4, a portion of a vertical support thereof, showing the detail of the grip finger latching mechanism; Fig. 5, a vertical section of the entire machine taken substantially on line 5—5, Fig. 2; and Fig. 6, a fragmentary view of the right end of the glue transfer roll assembly and its supports in the same operative position as shown in Fig. 5.

Similar numerals refer to similar parts in all views.

My machine consists generally of a rectangular supporting frame; a bottle rest to support bottles to be labeled; a label holder designed to hold a stack of labels; a glue pot to contain a supply of adhesive glue; a glue transfer roll to convey glue from the glue pot to the picker bars; picker bars to remove or pick labels from the said stack and convey them to the bottle to be labeled; a grip finger to hold the label in place on the bottle while the picker bars are removed; wipers to smooth or wipe the label down in place upon the surface of the bottle while it is held in place by the grip finger; and, lastly, mechanical mechanism for providing the necessary motions to the various moving parts, including a source of power to actuate same.

Referring to the drawings, numeral 1 designates, generally, the rectangular frame, composed of four vertical corner posts 2, a solid base

3 and suitable horizontal connecting members 4. At the right hand side of this frame, as viewed in Fig. 1, a bottle support 6 is provided which extends outward from the frame at its two sides and has a center section 7 extending inwardly 5 into the frame and terminating in a bottle rest 8, having an angular back 9 to aid in centering the bottle on the rest. This construction, shown particularly in Fig. 3, provides a rest so that the bottle may be placed in a position to receive the 10 labels and at the same time, allow the wipers to brush across the ends of the label, and face and sides of the bottle 10, as will be hereinafter explained.

A label holder 11 is swingably supported on a transverse shaft 12 near the top of frame 1. The supports 13 for this holder turn freely, or may be said to float, on shaft 12. At the opposite end of the label holder, a threaded bolt 14 is hingedly attached at 15 to the body of the holder 11 and extends upwardly through the top member 4 of the frame where a wing nut 16 is attached to provide adjustment. By this arrangement, the label holder frame is swingably adjustable on the axis of shaft 12, which coincides with the 20 axis of movement of the picker bars hereinafter described. Labels 16 are stacked within a rectangular box 17, of suitable size, at the adjustable end of the label holder body, wherein they are retained by fingers 18 in a manner according to the usual practice, and so that the bottom-most label may be separately removed by the picker bars. Picker bars 20 are mounted on shaft 12, by hubs 21 to swing therewith, the arc of their swing being indicated by broken lines 22 in Fig. 35 1, in which figure they are shown at the top of their swing engaging a label from stack 16. In Fig. 5, they are shown at the lower end of their swing (approximately ninety degrees), holding a label on the face of the bottle 10. They are positioned on shaft 12 to clear the sides of the bottle to be labeled, when at the lower limit of their swing. In order to provide this motion, shaft 12 is given an intermittent alternating torque motion through approximately ninety degrees. Depending upon the size and shape of the bottle to be labeled, picker bars 20 are provided with contact plates 23 at their outer ends, which actually receive the adhesive glue, and contact the bottom-most label in stack 16. 40 45 50

To supply these contact faces with glue, they are brought in rolling contact with glue transfer roll 24, which is supported on the swinging arms 25, attached at their lower ends to a transverse shaft 26, the axis of which is so placed within the 55

frame work that the transfer roll moving through an arc indicated by broken line 27 in Fig. 1, swings from a position against transfer roll stops 28 at the right end of its swing, to and against 5 a glue pot roller 29 at the left end of its swing. The extremities of these motions are indicated in solid lines in Figs. 5 and 1 respectively; also by the solid lines in Fig. 5, and the dotted outline 30 in the same figure. Glue pot roller 29 is supported within the vessel, or glue pot, 31 and caused to turn in a clock-wise direction by a pulley 32 driven by a belt 33. The glue pot or fountain contains liquid glue or adhesive, 34, of a tacky consistency, to the level shown in the 10 section in Fig. 5.

A grip finger 40 is mounted on a bearing hub 41, to turn freely or float on the transverse shaft 42. It is actuated by a crank 43, driven by a push rod 44. On the face which contacts the 15 bottle, the grip finger is provided with a soft contact face 45, preferably made of soft rubber. In operation, the grip finger swings from the position shown in Fig. 1, upward to the position indicated by the dotted outline 46 in said figure, and by the solid lines shown in Fig. 5, where it holds the label brought down from stack 46 by picker bars 20 in place upon the face of bottle 10. The lower end of push rod 44 engages a clevis 47 on the end of the grip finger push 20 rod actuating bar 48, mounted on, and to turn with, transverse shaft 49 by hub 50. The pin 51 which forms the actuating connection between push rod 44 and its actuating bar 45, passes through a slot 52 in said push rod, which, together with the coupling spring 53 surrounding 25 said rod and fastened at its upper end by pin 54, permits the grip finger 40 to be held in its upper, or actuating, position resiliently. The tension of spring 53 (which is an open spring) is 30 adjusted so that, in its upper position, grip finger face 45 is pressed against the face of bottle 10 with sufficient firmness to hold the label in place, but to in no wise crush the bottle. This tension may be adjusted by the opening 35 of spring 53 itself, or in altering the vertical position of pin 54 on rod 44. A clevis 55 at the upper end of push rod 44 communicates its reciprocating motion to the crank 56, upon which the lower end of the grip finger is attached. The 40 labels are smoothed in place upon the bottle by a pair of wipers 60, which I provide in the form of 45 brushes shaped as partial sectors of a circle, supported on, and attached to resiliently turn with, shaft 42, by hub 61, connected through torsional 50 flexing springs 62 to said shaft. The bristles 63 of each of these wipers point inwardly toward bottle 10, and the back of the bristles, which constitutes the body of the wiper, is positioned so that the bristles brush across the face of the 55 label as placed on the bottle, smoothing it down against the face and sides thereof. Their motion is effected by the simple rotation of shaft 42 on which they are mounted.

To provide acceleration during that portion 60 of the revolution of shaft 42 just preceding the wiping operation, a horizontal wiper latching bar 36 connects the two vertical transfer roll supports 25, and extends outward to form a latch contact 37 to engage the on-coming edge of the 65 wipers 60, as they rotate as shown. This permits the wipers to be positioned on their shaft so that a longer time is given for the removal of the labeled bottle and the placing of a bottle to be labeled. Their position being in a somewhat advanced position on the shaft to that

which it would otherwise have to be. Upon reaching latch contacting position they are retained until the picker bars move out of the way. When released they spring forward and immediately commence the wiping operation. 5

To provide the various motions necessary to complete the cycle of operations of the several parts above described, a system of cranks, connecting rods and their respective cross heads is provided. Attached at the left end of shaft 42 10 as shown in Fig. 2, is a driving crank 65, coupled through a connecting rod 66 to a driven crank 67 on shaft 12. The throw of crank 65 is gauged so that crank 67 will move through approximately ninety degrees, thus giving shaft 15 12 an alternating rotary movement.

In Fig. 1, crank 67 is shown at approximately the upper extreme of its motion. Connecting rod 66 is shown broken away in this figure, to better illustrate the position with the other other 20 cranks on shaft 12.

The outermost of these cranks is glue transfer roll driving crank 68, keyed thereon and operating through connecting rod 69 to drive glue transfer roll driven crank 70 on shaft 26. 25 Cross head 71 on this connecting rod is provided with a slot to permit delayed action in the actuating of crank 70. On the up stroke of crank 68, the crank pin on driven crank 70 slides in the slot 72 in cross head 71, while the glue 30 transfer rolls 24, together with their supporting arms 25, remain in the position as shown in Fig. 1, until crank 68, traveling in the direction of the arrow, nears the position indicated by the dotted outline 73. In the last portion 35 of this movement and after the crank pin in driven crank 70 has traveled in slot 72 to the end thereof, actuation takes place and throws crank 70 to the right, thus turning shaft 26, supporting arms 25, and glue transfer rolls to the position shown in Fig. 5, where they are 40 retained under the tension of spring 74, Fig. 6, which is positioned on crank 75 at the opposite end of shaft 26, and is positioned across the dead center axis of said shaft to resiliently hold the glue transfer rolls in either of the two positions; that is, either against stops 28 or in contact with glue pot roll 29. At this point it is noted that the left hand stop 28, as shown in Fig. 2, is broken away to better illustrate the 45 mechanism back of it. 50

On the downward movement of crank 68, the cross head 71 merely slides on the crank pin on crank 70, since the movement of the picker bars has, by this time, thrown the glue transfer roll past dead center and they are then held against glue pot roll 29 under the influence of spring 74. 55

The innermost crank on shaft 12, which I call the grip finger driving crank 77, is also keyed to turn therewith. Through connecting rods 78 and crank 79, this reciprocating motion is communicated to shaft 49, on which grip finger actuating bar 48 is affixed. Normally, grip finger actuating bar 48 is down in the position indicated in Fig. 1. However, as crank 77 traveling counter-clock-wise in the direction of the arrow approaches the dotted outline 80, the delayed motion cross head 81 actuates the crank pin on crank 78 to move it to the position indicated by the dotted outline 82, which results in moving bar 48 to the position indicated by the dotted outline 83, Fig. 1. This is the same position as indicated in solid lines in Fig. 5.

At this terminus of its movement, shaft 49 75

is held in position by the engagement of a single toothed ratchet 84 with a pawl latch 85, which is attached to the right hand supporting leg of frame 1, as view in Fig. 2. Details of this latch mechanism are shown in Fig. 4, wherein it is in releasing position. Latch 85 is resiliently held to engage ratchet 84 by a spring 26, and is moved out of engaging position by a cam 87, carried on shaft 42. With shaft 49 and bar 48 in the position indicated in Fig. 5, grip finger 40, being swung upward, is held against bottle 10. When shaft 42 assumes the position shown in Figs. 1, 2 and 3, cam 87 trips latching bar 85, releasing ratchet 84, thus permitting grip finger actuating bar 48 to return to the position indicated in these figures, by reason of its weight and the return spring 88.

Shaft 42 is driven in a clock-wise direction, as indicated by the arrows, by means of a belt 90 passing over pulley 91 thereon and receiving motion from a driving pulley 92 on a counter shaft 93, which is, in turn, driven by a belt 94 connecting pulley 95 on said shaft to motor 96. A smaller pulley 97 on shaft 93 accommodates belt 33, driving glue pot roll as above explained. The rotary motion of the wiper brushes 60 is indicated by the broken line 98.

Operation of the machine is as follows:

Starting at an initial point as indicated in Fig. 1, with bottle 10 having just received a label and wipers moving out of position and away from the bottle, and grip finger 40 being released, bottle 10 may be removed and replaced, manually, by a bottle to be labeled. After this is done, picker bars 20 having just received a fresh label from the stack 16, move downward to the position indicated in Fig. 5, whereby they carry the label, whose position is indicated by numeral 99, to the face of bottle 10. Grip finger 40 is then actuated through the mechanism above described, and holds the label in place while the picker bars start their motion upward, leaving the label coated with liquid adhesive glue where it has been in contact with plates 23.

In the meantime, glue transfer roll 24 having received a fresh supply of liquid adhesive glue by rolling on glue pot roll 29, has been moved to the position indicated in Fig. 5. In this position it is free to contact plates 23 on picker bars 20 as they move upward. The intersection of the arcs of their movements, as indicated by broken lines 22 and 27, indicates their relative positions during the upward movement of the picker bars. From this construction and relative position of these parts, it is obvious that the plates 23 on the picker bars will contact roll 24, which will roll across their face as they move it toward the left. This moistens the face of plates 23 with a fresh supply of glue.

After picker bars have moved out of the way of the motion of rotary brushes 60, these brushes released from latch 36 by the motion of glue transfer roll supports 25, rotate toward the face of bottle 10, as above explained. As shaft 42 continues to rotate, these brush wipers smooth the label in place, while it is being held against the face of the bottle by the resilient face 45 of grip finger 40. As soon as the brushes have passed out of contact with the bottle, cam 87 actuates latch 85 and the grip finger releases the bottle so that it may be manually removed with the label affixed thereon. A new bottle is then placed on rest 8 and the cycle of operations is repeated.

While I have herewith described the preferred

form of my machine, it is obvious to those familiar with the art, that various changes and modifications can be made to adapt the machine to various sizes and shapes of bottles, or other containers to be labeled. Thus it is conceivable that the brushes or bristles of wiper 60 may be replaced with sponge rubber or other light substance. It is also conceivable that their contacting faces may be made rotary, or even that they may be mounted so as to contact the face of bottle 10 by an alternating of reciprocating motion in brushing by the sides of the bottle as herewith shown. This construction might be particularly adapted to labels applied to a flat faced bottle.

It is to be understood that although "bottle" is mentioned in the title hereof, in this description and in the hereinafter claims, the word "bottle" is deemed to include other than glass containers; e. g., can containers.

All these changes and modifications, however, would remain within the spirit and conception of my invention as herewith disclosed, and I, therefore, wish to be limited only by the following claims.

I claim:

1. In a machine of the class described, a pair of wipers positioned on either side of the face of the bottle to be labeled and supported on a rotating shaft and having pliant bristles attached to their opposing faces, said wipers being rotatively supported on said shaft resiliently by a torque tension spring, and latching means cooperative therewith to detain the rotation of said wipers at a pre-determined position during a portion of the period of their rotation.

2. In a bottle labeling machine, a shaft; a wiper loosely supported on the shaft and positioned to press a label upon a bottle, a torsional spring connection between the shaft and the wiper, and means operatively connected to actuate the shaft to effect the label pressing operation.

3. In a bottle labeling machine, a shaft, opposed wipers loosely supported on the shaft and positioned to press a label upon a bottle, torsional spring connection means between the shaft and the wipers, and means operatively connected to actuate the shaft to effect the label pressing operation.

4. In a bottle labeling machine, a shaft, opposed wipers loosely supported on the shaft, pliant bristles on the opposed faces of the wipers to press a label upon a bottle, torsional spring connection means between the shaft and the wipers, and means operatively connected to actuate the shaft to effect the label pressing operation.

5. In a bottle labeling machine, a rotary shaft, opposed wipers loosely supported on the shaft 60 and positioned to press a label upon a bottle, torsional spring connection means between the shaft and the wipers, and means to rotate the shaft continually in a given direction.

6. In a bottle labeling machine, wiping means positioned to press a label upon a bottle by movement in the cycle of operation of said means, mechanism to actuate said means to effect said movement, and spring means arranged to be placed under tension prior to said movement of the wiping means, and said spring means being connected to cause a snap action of the wiping means during said predetermined movement.

7. In a bottle labeling machine, rotary wiping means disposed to press a label upon a bottle

during a portion of its rotation, mechanism to effect such rotation of the wiping means, and means to retard the rotation of the wiping means temporarily, prior to the label pressing action.

5 8. In a bottle labeling machine, rotary wiping means disposed to press a label upon a bottle during a portion of its rotation, mechanism to effect such rotation of the wiping means, means to cause a lag of the wiping means prior to the 10 label pressing action, and spring means to accelerate the rotation of the wiping means during the label-pressing action.

9. In a bottle labeling machine, wiping means positioned to press a label upon a bottle, mechanism to supply adhesive to labels for bottles, including an adhesive transfer roller, a swinging support for said roller, and a stop on said support, the stop being arranged to oppose movement of the wiping means when the roller is 20 swung to an adhesive transferring position.

10. In a bottle labeling machine, the combination of a supporting frame having a bottle rest, of a magazine for labels, picker bar means mounted to move from a label-contacting position at 25 the magazine to the face of a bottle on the bottle rest, a glue fountain, a glue transfer roll mounted to move from the glue fountain to a position contacting the picker bar means, to transfer glue thereto, wiping means positioned to press a label 30 upon a bottle by a predetermined movement, and a stop, controlled by the glue transfer roll, opposing movement of the wiping means to a bottle on the rest until the picker bar means has moved away from such bottle.

35 11. A bottle labeling machine, having picker bar means to transfer a gummed label from a magazine to a bottle on a rest and having a roll to transfer adhesive from a fountain to the picker 40 bar means characterized by an over-center spring means to snap said roll to either of its said positions, the spring causing the roll to move to a position in which it effects resilient pressure of

the roll upon the picker bar means to insure firm contact of the one with the other.

12. A bottle labeling machine, having picker bar means to transfer a gummed label from a magazine to a bottle on a rest and having a roll 5 to transfer adhesive from a fountain to the picker bar means, characterized by spring means to resiliently maintain the roll in its position at the fountain, to insure a good transfer of adhesive from the fountain to the roll. 10

13. A bottle labeling machine, having picker bar means to transfer a gummed label from a magazine to a bottle on a rest and having a roll to transfer adhesive from a fountain to the picker 15 bar means, characterized by an overcenter spring 15 means to snap said roll to either of its said positions, depending upon which side of dead center the roll is disposed, the picker bar means being mounted to move the roll past dead center, whereby the roll snaps to its position at the adhesive 20 fountain.

14. A bottle labeling machine having picker bar means to transfer a gummed label from a magazine to a bottle on a rest and having a roll to transfer adhesive from a fountain to the picker 25 bar means, characterized by means to delay the action of the roll in transferring adhesive to the picker bar means until the picker bar means has transferred a gummed label from the magazine to a bottle on the rest, to avoid applying adhesive to 30 the outer face of the label.

15. A bottle labeling machine, having picker bar means to transfer a gummed label from a magazine to a bottle on a rest and having a roll to transfer adhesive from a fountain to the picker 35 bar means, characterized by slotted driving means for actuating the roll in transferring adhesive to the picker bar means, the slot being so arranged that the roll is not so actuated while the picker bar means is transferring a gummed label from 40 the magazine to a bottle on the rest, to avoid applying adhesive to the outer face of the label.

GEORGE M. BINER.
